UNITED STATES PATENT OFFICE

GERTRUDE MOESSNER, OF NEW HAVEN, CONNECTICUT, ASSIGNOR TO THE SEAMLESS RUBBER COMPANY, INC., OF NEW HAVEN, CONNECTICUT, A CORPORATION OF MASSACHUSETTS

DESIGN FOR A HEATING PAD OR SIMILAR ARTICLE

Application filed July 1, 1931. Serial No. 40,391. Term of patent 14 years.

To all whom it may concern:

Be it known that I, GERTRUDE MOESSNER, a citizen of the United States, residing in New Haven, in the county of New Haven and State of Connecticut, have invented a new, original, and ornamental Design for a Heating Pad or Similar Article, of which the following is a specification, when taken in connection with the accompanying drawings, in which—

Figure 1 is a face view of a heating pad showing my new design, and Figure 2 is an edge view of the same.

I claim:

The ornamental design for a heating pad or similar article, substantially as shown.

GERTRUDE MOESSNER.
